(57) CLAIM

The ornamental design for a bathroom cabinet, as shown and described.

DESCRIPTION

FIG. 1 is a front, right, and top perspective view of a bathroom cabinet, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a perspective view of the bathroom cabinet of FIG. 1 wherein an inter-panel and a door of the bathroom cabinet are open.

The broken lines shown in the drawings are included for the purpose of illustrating portions of the bathroom cabinet that form no part of the claimed design.
